UNITED STATES PATENT OFFICE

2,105,365

ACCORDION

Roberto Pancotti, Nutley, N. J., assignor to Ex-
celsior Accordion Manufacturing Co., Inc., New
York, N. Y.

Application May 13, 1936, Serial No. 79,424

4 Claims. (Cl. 84—376)

The present invention relates to musical instruments, and more particularly to accordions.

In accordions as heretofore constructed, the valve and sound chambers or heads have sharp or square corners formed by joining together the side and end walls of said chambers at right angles to each other. Similarly in such accordions the bellows have sharp corners conforming to the contour of the walls of the sound chambers or heads of the accordion. I have found that the tonal qualities of the accordion are greatly improved when the walls of the sound chamber, instead of being joined at right angles, are provided with well rounded corners or curved portions. The provision of rounded corners in the bellows in conformity with the rounded corners of the valve and sound chambers or heads also contributes to the improvement of the tonal qualities of the instrument and further results in quicker tone response to the movement of the bellows. The tone produced in the playing of accordions having rounded corners in accordance with the present invention has greater richness and in this and other respects is more pleasing than the tone of the square corner accordions such as those which were conventional prior to my invention. The provision of an accordion of improved tonal qualities and which has a substantially instantaneous tone response to the movement of the bellows are primary objects of the present invention.

A further object of the invention is to improve the construction of the bellows whereby the life thereof may be lengthened. This is accomplished in accordance with the present invention by the provision of rounded corners in the bellows which results in deep bellows folds whereby to improve the tone response to the movement of the bellows and to reduce the strains and movement of the bellows that contribute to the failure or break down thereof.

The above objects of the invention and other objects which might hereinafter appear will be fully understood from the following description considered with reference to the accompanying drawing.

In the drawing:—

Fig. 1 is a perspective view of an accordion embodying the present invention;

Fig. 2 is a sectional view on the line 2—2 of Fig. 1;

Fig. 3 is a sectional view on the line 3—3 of Fig. 1;

Fig. 4 is a sectional view on the line 4—4 of Fig. 1;

Fig. 5 is a view similar to Fig. 2, showing a modification;

Fig. 6 is a sectional view on the line 6—6 of Fig. 5.

Referring to the drawing, the accordion, indicated generally by the reference numeral 10, comprises the usual keyboards 12 and 14, the bellows 16 and two valve and sound chambers or heads 18 and 20 adjacent said keyboards 12 and 14, respectively, on opposite sides of the bellows. 10 In accordance with the usual construction of accordions a reed and valve block 22 is mounted within the valve and sound chamber 18 and similarly a reed and valve block 24 is mounted with 15 in the sound and valve chamber 20. The valve and sound chamber 18 is defined by side walls 26 and 28 and by end walls 30. The other valve and sound chamber 20 is similarly defined by side walls 32 and 34 and by end walls 36.

As clearly shown in Figs. 2 and 3, the end and 20 side walls of said chambers 18 and 20 do not meet each other at right angles, but merge into each other at their adjacent end portions along well rounded curved lines forming instead of right angular corners, as in the prior art constructions, internal and external well rounded corners or curved portions 38 and 40 in the chambers 18 and 20, respectively. Also, as clearly shown in Figs. 2 and 3, said side and end walls 25 of both sound chambers are formed respectively from continuous strips of material, such as wood, bent into the configuration shown to provide the chamber defining walls with well rounded end portions and joined at their meeting ends 42 and 44, respectively, here shown positioned midway of the side walls 26 and 34 of the sound 30 chambers 18 and 20, respectively. By reason of this construction, the plurality of joints heretofore required in instruments of this character are eliminated. The sound chambers 18 and 20 35 are provided with covers 19 and 21, respectively, which may be of any preferred or conventional construction which, while permitting the emission of sound, exclude dust and serve also as ornamental elements for the accordion. 40

The bellows 16 may be of any usual construction, but for better results in the playing of the instrument and in order to harmonize with the appearance of the sound chambers 18 and 20, 50 said bellows preferably conform in peripheral configuration to the peripheral contour of the sound and valve chambers 18 and 20. Thus, as shown in Fig. 4, the side walls 46 and the end walls 48 of the bellows have rounded corner or curved wall portions 50 in conformity with the 55

rounded portions 38 and 40 of the sound chambers 18 and 20.

In the form of the invention illustrated in Figs. 5 and 6, the sound chambers in communication with the bellows may comprise, as in the prior art constructions, side walls 51 and end walls 52, which are joined together at their meeting ends forming right angular corner portions. As here shown, however, a filler member 54 is positioned interiorly of the sound chamber at each corner portion thereof thus forming an internal rounded corner. Said filler members are substantially triangular in cross section, having angularly related outer surfaces 56 and 58 and an inner surface 60 which is preferably curved. Said filler members are set into recesses 62 and 64 formed in the side and end walls 51 and 52, respectively, at each corner portion of the sound chamber so that the curved surface of the wall 60 is continuous with the inner surfaces of the companion end and side walls of the sound chamber. In this form of the invention, the valve and reed block 23 is illustrated more or less conventionally as is the case with the valve and reed blocks 22 and 24 in the form of the invention shown in Figs. 2 and 3, it being understood that the present invention is not concerned with the details of construction of the accordion or any parts thereof other than the sound chambers and bellows. It will be further understood that in the construction illustrated in Figs. 5 and 6, the bellows instead of having rounded corner portions, as in the constructions illustrated in Fig. 1, have their side and end walls in right angular relation as in the prior art constructions.

Thus, it is seen that the constructions herein shown and described are well adapted to accomplish the several objects of the present invention. However, it will be understood, especially in connection with the form of the invention illustrated in Figs. 1 to 4, that the peripheral configuration of the body of the accordion, including the bellows and valve and sound chambers, is such that said body is free of sharp corners or other abrupt edges and on this account the accordion may be held against the player's body with considerable more comfort than was heretofore the case. It will be understood, however, that while I have shown several embodiments of my invention, including the one which I prefer, nevertheless, the

invention is capable of other embodiments and that certain changes in the construction and arrangement of parts may be made in the forms of the invention herein illustrated. Accordingly, I do not wish to be limited to the precise constructions herein shown or described, except as may be required by the appended claims considered with reference to the prior art.

Having described my invention, what I claim and desire to secure by Letters Patent is:

1. An accordion comprising a bellows and a valve and sound chamber in communication therewith, said chamber comprising side and end walls having their adjacent portions at both ends and sides of the chamber merged into each other along curved lines forming curved wall portions or rounded corners at the ends and sides of said chamber.

2. An accordion comprising a bellows and a valve and sound chamber in communication therewith, said chamber comprising side and end walls having their adjacent portions at both ends and sides of the chamber merged into each other along curved lines forming curved wall portions or rounded corners at the ends and sides of said chamber, said bellows also having rounded corners and conforming substantially to the contour of said side and end walls.

3. An accordion comprising a bellows and a valve and sound chamber in communication therewith, said chamber comprising side and end walls having their adjacent portions at both ends and sides of the chamber interiorly thereof merged into each other along curved lines forming curved wall portions or rounded corners at the ends and sides of said chamber interiorly thereof.

4. An accordion comprising a bellows and a valve and sound chamber in communication therewith, said chamber comprising side and end walls having their adjacent portions at both ends and sides of the chamber interiorly thereof merged into each other along curved lines forming curved wall portions or rounded corners at the ends and sides of said chamber interiorly thereof, said bellows also having rounded corners and conforming substantially to the contour of said side and end walls.

ROBERTO PANCOTTI.
